UNITED STATES PATENT OFFICE.

CHARLES SPIER, OF ST. LOUIS, MISSOURI, ASSIGNOR TO JOSEPH PETERS
FURNITURE COMPANY, OF SAME PLACE.

SECTIONAL KITCHEN-SAFE.

SPECIFICATION forming part of Letters Patent No. 232,772, dated September 28, 1880.

Application filed June 15, 1880. (No model.)

To all whom it may concern:

Be it known that I, CHARLES SPIER, of the city of St. Louis, in the State of Missouri, have invented a certain new and useful Improvement 5 in Sectional Kitchen-Safes, of which the following is a full, clear, and exact description, reference being had to the accompanying drawings, forming part of this specification.

10 My improvement relates to that class of kitchen-safes which are shipped from the factory to the merchant or user in a "knock-down" condition; and it consists, primarily, in constructing the frame of four sections, the 15 end uprights of which are arranged to fit against the outer ends of the front and back sections, and with them form a complete frame and legs.

The improvement also consists in certain details in construction, clearly pointed out in the specification and claims.

The frame is shown as constructed for the reception of a drawer; but this is not an essential part of my invention.

20 In the drawings, Figure 1 is a perspective view, with one end removed and shown in inside perspective, the top being absent, and also the gauze or perforated sheets of the doors to show the construction of the safe.

30 Fig. 2 is a horizontal section at *a a*.

A is the front of the safe, having half-legs *a'*, and *B* is the back of the safe, having half-legs *b*.

35 *C* are the ends, having half-legs *c c*, which, when the safe is completed, form, with the part legs *a'* and *b*, the legs of the safe. Thus the legs consist of two pieces each, making a strong leg with timber of common thickness. As the parts leave the factory for shipment the back 40 consists of the uprights or legs *b*, the cross-bars *b'*, and the siding pieces *b²*, fitting in

grooves of the uprights and bars. The front consists of the legs or uprights *a'*, the cross-bars *a²*, and the doors *a³*, hinged to the uprights. Each of the ends consists of the legs 45 or uprights *c*, the cross-bars *c'*, the perforated plates or gauze *c²*, and cleats *c³* and *c⁴*, which form guides in putting the end in place by contact with the inner sides of the front and back, and serve to give stability to the safe, 50 as well as forming support for the bottom and drawer.

It will be observed that, by having distinct uprights *a'* *a'* for the front, *b b* for the back, and *c c* for each side, I am enabled to form the 55 walls of the safe complete in four separate parts, in which the pieces are firmly framed together, so as to occupy but little more space than bare lumber, and the parts are attached together by common screws *D* in screw-holes 60 *d*, so that no mechanical knowledge is needed in putting up the safes, nor can they be put together out of square.

I claim as my invention—

1. A sectional kitchen - safe consisting of 65 four parts, *A B C C*, the front *A* having half-legs or uprights *a'*, cross-bars *a²*, and hinged doors *a³*, the back *B* having grooved half-legs or uprights *b*, grooved cross-bars *b'*, and sliding pieces *b²*, and the end sections, *C*, having 70 half-legs or uprights *c*, cross-bars *c'*, cleats *c³* *c⁴*, and gauze or perforated plates *c²*, substantially as and for the purpose set forth.

2. The sectional kitchen - safe herein described, having uprights and half-legs *a' b c c*, 75 the legs *c c* resting against and being secured to the legs *a' b*, as and for the purpose set forth.

CHS. SPIER.
